CLAIM

The ornamental design for a float device, as shown and described.

DESCRIPTION

FIG. 1 is a front perspective view of a first embodiment of a float device in accordance with our new design;

FIG. 2 is a rear perspective view thereof;

FIG. 3 is a top view thereof;

FIG. 4 is a right view thereof;

FIG. 5 is a left view thereof;

FIG. 6 is a front view thereof;

FIG. 7 is a rear view thereof;

FIG. 8 is a front perspective view of a second embodiment of a float device in accordance with our new design;

FIG. 9 is a rear perspective view thereof;

FIG. 10 is a top view thereof;

FIG. 11 is a right view thereof;

FIG. 12 is a left view thereof;

FIG. 13 is a front view thereof; and,

FIG. 14 is a rear view thereof.

The broken lines in the drawings illustrate portions of the float device that form no part of the claimed design.
